[57] CLAIM

[21] Appl. No.: 602,868

The ornamental design for a combined clockface and hands therefor, as shown and described.

DESCRIPTION

FIG. 1 is a front elevational view of a combined clockface and hands therefor showing my new design; FIG. 2 is a rear elevational view; and, FIG. 3 is a side plan view with the watch hands set at a different time, the opposite side being a mirror image thereof.
